V. H. NICKERSON.
CARTRIDGE FOR CLEANING WELL STRAINERS.
APPLICATION FILED JUNE 5, 1917.

1,275,462.

Patented Aug. 13, 1918.

UNITED STATES PATENT OFFICE.

VICTOR HALL NICKERSON, OF COTUIT, MASSACHUSETTS.

CARTRIDGE FOR CLEANING WELL-STRAINERS.

1,275,462.

Specification of Letters Patent. Patented Aug. 13, 1918.

Application filed June 5, 1917. Serial No. 172,893.

To all whom it may concern:

Be it known that I, VICTOR H. NICKERSON, a citizen of the United States, and a resident of Cotuit, in the county of Barnstable and State of Massachusetts, have invented a new and Improved Cartridge for Cleaning Well-Strainers, of which the following is a full, clear, and exact description.

My invention has for its object to provide a cartridge for cleaning well strainers which may be lowered in a driven well point or strainer while in the ground and be exploded to clean the strainer, which may have become clogged while in use.

Additional objects of the invention will appear in the following specification, in which the preferred form of the invention is disclosed.

In the drawings similar reference characters denote similar parts in all the views, in which—

Figure 1 is a sectional elevation illustrating the position of my cartridge in a well strainer;

Fig. 2 is an enlarged sectional view showing the cartridge illustrated in Fig. 1;

Fig. 3 is a sectional view on the line 3—3 of Fig. 2;

Fig. 4 is a sectional view on the line 4—4 of Fig. 2;

Fig. 5 is a sectional view on the line 5—5 of Fig. 2; and

Figs. 6 and 7 are sectional views illustrating modified forms of the invention.

By referring to the drawings, it will be seen that a cartridge 10 is lowered in the well lining 11 to a position at the strainer 12, the cartridge 10 being constructed of a tube 13 through which a wire 14 is dis-

posed, the said wire 14 being insulated except at one position 15 from which leads a terminal 16 which forms a spark gap with the tube 13 which is constructed of an electrical conducting material. The ends of

the tube 13 are closed by plugs 17 which have orifices 18 through which the wire 14 is disposed, the plugs 17 fitting snugly around the wire and against the ends of the tube 13 to prevent water from entering the

tube and damaging the explosive 19 disposed within the tube. The wire 14 extends below the tube 13 and to the lower end of the wire there is secured a weight 20 the diameter of which is greater than the inner diameter of the tube 13.

It will be understood that the cartridge

may be lowered into the well to a position at the strainer 12 by means of the wire 14; that the explosive 19 may be fired by passing a current through the wire 14 which will jump the spark gap to the tube 13, the said tube 13 being disposed in the water, which forms a conductor between the tube 13 and the strainer 12, which is connected with the lining 11 in the manner set forth. When the explosive 19, which should be of slow burning quality, is fired, the plugs 17 are blown out at the ends of the tube 13, and the pressure formed by the expanding gases will force water through the orifices 21 in the strainer 12, to clean the strainer. When the plugs 17 have been blown out, as stated, and the strainer has been cleaned, it is possible to remove the tube 13 from the well by drawing upwardly on the wire 14, the weight 20 engaging the end of the tube 13, in a manner readily understood.

In the form of the invention illustrated in Fig. 6 of the drawings, the explosive 22 is contained in a paper tube 23 which is shellacked or otherwise coated to prevent the explosive within the tube from becoming damaged by the water in the well. The ends of the paper tube 23 are secured around brass end pieces 24 in which rubber packing 25 is disposed. The outer ends of the end pieces 24 have inner threads 26. An outer screw 27 on a plug 28 meshes with one of the inner threads 26 to hold the packing 25 in position, the plug 28 and the said packing 25 having orifices 29 and 30 respectively, through which a wire 31 is secured to the other packing 25, the said other packing 25 being held in position by a screw member 32 which meshes with the inner thread 33 in the said brass end member 24.

It will be understood that when this form of the invention is used, the cartridge may be lowered in the well by the wire 31 and may be fired by passing a current through the wire 31, the said current jumping the gap to the terminal 35 and passing through the water to the strainer and well casing in the manner described.

In the form of the invention illustrated in Fig. 7 of the drawings, an elongated tube 36 is employed in the lower end of which a weight 37 is disposed, the explosive 38 being disposed in the tube 36 above the weight 37, and the top of the tube 36 being closed by the plug 39. There is an orifice 40 in the plug 39 through which a wire 41 is disposed,

this wire 41 having a terminal 42 in the tube 36 which is disposed adjacent terminal 43 on a conductor 44 which is in electrical contact with the tube 36, the said tube being constructed of electrical conducting material. Secured to the side of the tube 36 there is a member 45 having an opening 46 through which the wire 41 extends, the wire 41 being gripped by the member 45 at its orifice 46, so that after the explosive 38 has been fired in a manner readily understood, and the plug 39 has been blown from the tube 36, the wire 41 will still be secured to permit of the raising of the tube 36 when the wire 41 is drawn from the well.

Having thus described my invention, I claim as new and desire to secure by Letters Patent:

1. In a cartridge for cleaning well strain-
ers, a tube having a wall serving as an
electric conductor connecting the exterior
with the interior of the tube, a conductor
connected with the wall, an explosive in the
tube, a wire secured to the tube and extend-
ing therein to form a spark gap with the
last conductor, the wire serving to lower the
tube in a well and to remove the tube after
the explosive has been fired to clean the
strainer in the well.
2. In a cartridge for cleaning well strain-
ers, a tube having a wall serving as an
electric conductor connecting the exterior
with the interior of the tube, a conductor
connected with the wall, an explosive in the
tube, a plug in the end of the tube which will
be blown out when the explosive is fired, a
wire extending within the tube to form a
spark gap with the last conductor, the wire
serving to lower the tube into a well and to
remove the tube after the explosive has been
fired and the plug has been blown from the
tube.

3. In a cartridge for cleaning well strain-
ers, a tube having a wall serving as an
electric conductor connecting the exterior 45
with the interior of the tube, a conductor
connected with the wall, an explosive in the
tube, a portion of the tube being constructed
to open to free the gases when the explosive
is fired, and a wire extending into the tube 50
to form a spark gap with the last conductor,
the wire serving to lower the tube in a well
and to remove the tube after the explosive
has been fired to clean the strainer in the
well. 55

4. In a cartridge for cleaning well strain-
ers a tube having a wall serving as an
electric conductor connecting the exterior
with the interior of the tube and an ex-
tending member with an orifice, a weight 60
secured to the tube, an explosive in the tube,
a plug closing the upper end of the tube and
having an orifice extending therethrough, a
conductor secured to the plug and having
contact with said wall of the tube and pro-
vided with a terminal in the tube, and a
wire extending through the orifices in the
extending member of the tube and in the
plug and provided with a terminal forming
a spark gap with the first terminal. 65

5. In a cartridge for cleaning well strain-
ers, a tube having a wall serving as an
electric conductor connecting the exterior
with the interior of the tube, a weight se-
cured to the tube, an explosive in the tube, 75
a plug closing the upper end of the tube and
having an orifice extending therethrough, a
conductor secured to the plug and having
contact with the said wall of the tube and
provided with a terminal in the tube, and a 80
wire extending through the orifice in the
plug and provided with a terminal forming
a spark gap with the first terminal. 70

VICTOR HALL NICKERSON.
